UNITED STATES PATENT OFFICE.

THOMAS NATHAN RUSSELL, OF CHICAGO, ILLINOIS, ASSIGNOR TO CHICAGO-CLEVELAND CAR ROOFING CO., OF CHICAGO, ILLINOIS, A CORPORATION OF ILLINOIS.

CAR-ROOF.

1,177,814.

Specification of Letters Patent.

Patented Apr. 4, 1916.

Application filed August 19, 1915. Serial No. 46,287.

To all whom it may concern:

Be it known that I, THOMAS NATHAN RUSSELL, a citizen of the United States, residing in Chicago, in the county of Cook and State of Illinois, have invented a new and useful Improvement in Car-Roofs, of which the following is a specification.

The invention relates to outside car roofs, and more particularly to such roofs having a roof lining or insulation applied at the under sides of the roof sheets. Under some climatic conditions and extremes of temperature change, and particular character of the load within the car, moisture within the car condenses and collects upon the under sides of the metallic roof sheets. This condition is commonly called sweating and it is the object of the present improvement to prevent such condition under any circumstances.

The invention comprises a structure of the longitudinal members of the car roof frame, such as the ridge pole and purlins, whereby said members are adapted to hold the described insulation at the under sides of the roof sheets, when such sheets have their under faces at or near the same horizontal plane as the bottom faces of the car lines.

The invention further relates to all new features of advantage, which are, broadly or specifically, inherent in my improved roof.

The invention consists in the parts and combinations thereof, hereinafter set forth and claimed.

In order to make the invention more clearly understood there are shown in the accompanying drawings means for carrying the same into practical effect without limiting the improvements in their useful applications, to the particular construction which, for the purpose of example has been illustrated.

In said drawings—Figure 1 is a plan view of a portion of the car roof embodying the invention certain of the parts being broken away to better illustrate the construction. Fig. 2 is a side view of the same. Fig. 3 is a vertical cross section of a portion of the roof on a larger scale. Fig. 4 is a similar section of the eaves portion of the roof, on a still larger scale. Fig. 5 is a vertical section, of about full size, of a portion of the roof, taken longitudinally

of the car at or near the ridge pole. Fig. 6 is a vertical sectional view taken longitudinally of the car at or near the ridge pole, showing a portion of the roof at one end of the car. Fig. 7 is a plan view of the carline. Fig. 8 is a side view of the same. Fig. 9 is an end view of the same. Fig. 10 is a plan view of one of the longitudinal members, such as the ridge pole or a purlin. Fig. 11 is a side view of the same; in Figs. 10 and 11 the middle portion of the member is broken away. Fig. 12 is a plan view of one of the roof sheets. Fig. 13 is an end view of the same.

Referring to the drawings, the upper part of the car body frame constitutes the roof frame, and it comprises side plates which are or may be of what is known as Z cross section, having a vertical web 1, an inwardly extending top flange 2 and an outwardly extending bottom flange 3. The side plates are united at the ends of the frame by end plates 4 which may be arched to conform to the roof. The above described roof frame members are carried by 75 posts or stakes and braces of known construction.

5 is the side sheathing and 6 the end sheathing.

7 indicates the carlines arranged at suitable intervals along and resting on the top flanges 2 of the side plates. The carlines are arched from side to side of the car, and are formed with a bottom central web portion 8, from which extend upwardly side flanges 9. Each side flange terminates in a substantially semi-circular curved lip or flange 10 having its concave side presented downward. At its ends the carline is formed with horizontal bottom seats 11 95 which are secured to the side plates by rivets or bolts 12.

At its ends the carline terminates in vertical flanges 13 turned down over and at the under sides of the side plates, each of said flanges 13 being perforated by a hole 14 for a rivet 15 which secures the carline to the side plate. The flanges 9 and 10 terminate at the upper part of the flange 13, and in line with them the flange 13 confines the adjacent ends of the downturned eaves flanges 16 of the roof sheets against the side plate 1, said flange 10 being recessed at 17 (Figs. 7 and 8) to fit over and confine such eaves flanges. Between the 105

55 a portion of the roof, taken longitudinally

carlines the flanges 16 are secured to the side plates by bolts 18.

19 is the ridge pole and 20 the purlins, being longitudinal members of the roof frame, all of which members may be of the same construction, as seen in Figs. 10 and 11. They are shallow inverted channel irons having a middle web 21 riveted to the web 8 of the carlines at 22 and side flanges 10 23 located about a half inch below the web 21. The ends of these longitudinal members are recessed at 24 to fit under the end plate flange 25 to which they are riveted (Fig. 6).

The roof sheets are shown at 26 and extend 15 from side plate to side plate, and are formed at their side edges with S-shaped flanges 27 which fit tightly within the flanges or lips 10 of the carlines (Fig. 5).

28 is an insulation-supporting plate secured 20 to the side plate, preferably by the rivets 12 and having its inner edge spaced about one half of an inch from the under sides of the carlines and roof sheets, the under sides of the latter being substantially 25 flush with each other as shown. The said insulation is shown at 29, being preferably in the form of tongued and grooved sheathing of about one half of an inch in thickness. This insulation extends substantially from 30 side plate to side plate, arched to correspond with the arch of the roof (Fig. 3), but the same is not necessarily continuous. As shown it is made in two sections for each 35 side of the roof. The outer section is supported by the plate 29 and the outer flange 23 of the purlin, the inner section being supported by the inner flange 23 of said purlin and the opposing flange 23 of the ridge pole; and the two sections at the other side of 40 the ridge are correspondingly supported.

30 is a flashing having a hook flange on the top of the side plate and a vertical flange confined on the outer side of the side plate under the roof sheet flanges (Fig. 4). The outer section of the insulation abuts against 45 the hook of the said flashing. In the absence of this flashing, and of the plate 29, the outer edge of the insulation would rest on the top of the side plate. The insulation does not necessarily sustain the roof. It 50 may stiffen it, but it is suspended at the underside of the water excluding members.

In the construction illustrated the roof sheets are supported by the elevated middle portions 55 of the ridge pole and purlins, independently of the insulation. But the invention does not exclude a construction in which all portions of the longitudinal members are a little (say one half inch) below the bottom 60 of the carlines, in which case the sheets would be supported by the insulation, and the latter in turn by the longitudinal members.

The parts of the insulation are preferably fitted in place as the process of applying

the roof sheets in place proceeds. But they may be sprung into place from below after the roof has been otherwise completed. The said insulation is indirectly suspended from the carlines, and covers the under sides 70 of the roof sheets and carlines, excepting where it is or may be interrupted by the longitudinal members.

What is claimed is:

1. In a car roof, in combination: side plates, 75 carlines, longitudinal members and metallic roof sheets, and an insulation material suspended on said longitudinal members at the under sides of the roof sheets and carlines.

2. In a car roof, in combination: side plates, 80 carlines, longitudinal members and metallic roof sheets, and an insulation material under the roof sheets and carlines and arranged in sections separated and supported by the said longitudinal members. 85

3. In a car roof, in combination: a frame comprising side plates, carlines, and longitudinal members arranged under and attached to the carlines; metallic roof sheets engaging the carlines; said longitudinal 90 members having depending and laterally extended flanges arranged at a distance from the under sides of the roof sheets; and an insulation material carried by the said flanges of the longitudinal members at the 95 under sides of the roof sheets. 95

4. In a car roof, in combination: a frame comprising side plates, carlines, and longitudinal members arranged under and attached to the carlines and having laterally 100 extending flanges arranged at a distance from the under sides of the metallic roof sheets; roof sheets engaging the carlines and having their under sides substantially level with the under sides of the carlines; and an 105 insulation material in the form of tongued and grooved wooden sheathing carried by the said flanges of the longitudinal members at the under sides of the roof sheets and carlines. 110

5. In a car roof, in combination: a frame comprising side plates, carlines, and longitudinal members attached to the carlines; metallic roof sheets engaging the carlines and having their under sides substantially 115 level with the under sides of the carlines; and an insulation material carried by the said longitudinal members at the under sides of the roof sheets. 115

6. In a car roof, in combination: a frame 120 comprising side plates, carlines, and a ridge pole and purlins arranged under and attached to the carlines; metallic roof sheets engaged by the carlines and having their under sides substantially level with the under sides of the carlines; said ridge pole and purlins having laterally extending flanges arranged at a distance from the under sides of the roof sheets; and an insulation material in the form of tongued and grooved 125

130

wooden sheathing carried by the said flanges of the ridge pole and purlins at the under sides of the roof sheets.

7. In a car roof, in combination: a frame comprising side plates, carlines formed with upstanding side flanges and outwardly and downwardly curved lips, and longitudinal members of laterally flanged inverted U-shape and arranged under and supported by the carlines; metallic roof sheets arranged over the longitudinal members and engaged under the lips of the carlines; and an insulation material carried by the lateral flanges of the said longitudinal members and arranged in the spaces between the longitudinal members and at the under sides of the roof sheets.

8. In a car roof, in combination: a frame comprising side plates, carlines formed with upstanding side flanges and outwardly and downwardly curved lips, and longitudinal members of laterally flanged inverted U-shape and arranged under and supported by the carlines; metallic roof sheets arranged over the longitudinal members and engaged under the lips of the carlines; and an insulation material in the form of tongued and grooved wooden sheathing carried by the lateral flanges of the said longitudinal members and arranged in the spaces between the longitudinal members and at the under sides of the roof sheets.

9. In a car roof, in combination: a frame comprising side plates, carlines formed with upstanding flanges and outwardly and downwardly turned lips, and longitudinal members of laterally flanged inverted U-shape and arranged under and attached to the carlines; metallic roof sheets arranged over said longitudinal members and engaging under and confined by said lips of the carlines; and an insulation material at the under sides of the roof sheets, and below the tops of and between the longitudinal members.

10. In a car roof, in combination: a frame comprising side plates, carlines formed with upstanding flanges and outwardly and downwardly turned lips, and longitudinal members of laterally flanged inverted U-shape arranged under and attached to the carlines; metallic roof sheets arranged over said longitudinal members and engaging under and confined by said lips of the carlines;

and an insulation consisting of wooden strips extending crosswise of the car and confined between the under sides of the roof sheets and carlines and the flanges of the said longitudinal members.

11. In a car roof, in combination: a frame comprising side plates, having supports extending inward therefrom, carlines formed with upstanding flanges and outwardly and downwardly turned lips, and longitudinal members of laterally flanged inverted U-shape arranged under and attached to the carlines; metallic roof sheets arranged over said longitudinal members and engaging under and confined by said lips of the carlines; and an insulation material at the under sides of the roof sheets, and resting on said supports and on the lateral flanges of the longitudinal members below the tops of and between the longitudinal members.

12. In a car roof, in combination: a frame comprising Z-formed side plates having supports attached to their top flanges and extending inward, carlines formed with bottom webs, upstanding side flanges and outwardly and downwardly turned lips, and longitudinal members of laterally flanged inverted U-shape arranged under and attached to the carlines; hook-flashings on the said top flanges of the carlines; metallic roof sheets arranged over said longitudinal members and engaging under said lips of the carlines; and a tongued and grooved wood insulation the members of which extend cross-wise of the car under the roof sheets and carlines and are confined by the said supports and flashings and the sides and flanges of the said longitudinal members.

13. In a car roof, in combination: a car roof frame comprising side plates having inwardly extending top flanges, outwardly extending bottom flanges and vertical webs; carlines arched from side plate to side plate across the car; longitudinal members supported by the carlines; roof sheets arranged between the carlines and over said longitudinal members; and an insulation material arranged under said carlines and roof sheets and supported by said longitudinal members.

In testimony whereof I have hereunto set my signature.

THOMAS NATHAN RUSSELL.
